UNITED STATES PATENT OFFICE.

GEORGE M. PURVER, OF BROOKLYN, NEW YORK.

DESIGN FOR A WRIST-WATCH HOLDER.

51,239.

Specification for Design.

Patented Sept. 4, 1917.

Application filed July 30, 1917. Serial No. 183,624. Term of patent 7 years.

To all whom it may concern:

Be it known that I, GEORGE M. PURVER, a citizen of the United States, residing in the borough of Brooklyn, county of Kings, and State of New York, have invented a new, original, and ornamental Design for Wrist-Watch Holders, of which the following is a specification, reference being had to the accompanying drawing, forming a part thereof.

Fig. 2 is a side view of the same wrist watch holder, showing my new design.

I claim:

The ornamental design for a wrist watch holder, as shown.

GEORGE M. PURVER.

Witnesses:

BERNARD COWEN,
HYMAN GOLDSTEIN.
